INTAGLIO-ENGRAVED-PLATE, FLAT BED
PRINTING PRESSOliver A. Quayle, Sr., Albany, N. Y., assignor to
Albany Monroe Corporation, Albany, N. Y., a
corporation of New York

Application January 12, 1932. Serial No. 586,179

12 Claims. (Cl. 101—158)

My invention more particularly relates to intaglio-engraved-plate, flat bed printing presses and especially to the means for the feeding, printing and delivery of wet or dry paper in sheet, 5 sheets or roll form.

Intaglio-engraved-plate, flat bed printing presses are ordinarily so constructed as to require the manual feeding of sheets of wet or dry paper of restricted sizes, and the sheets of paper so fed 10 must be sufficiently small in size to permit of their removal from the said plate while it is in motion. In order that the ink resulting from an impression shall not smudge or otherwise offset from one impression to another impression when the 15 said sheet is removed when delivery occurs, the insertion of intervening or slip sheets between the printed sheets is necessary, all of which operations are manually performed. The stacking of wet sheets of paper with intervening or slip sheets 20 which exclude the air from the wet paper materially retards the drying thereof which results in much delay and inconvenience.

The several recited operations confine the speed at which printing may be performed upon an 25 intaglio-engraved-plate, flat bed printing press to a degree which will afford the operator sufficient time either to feed the sheet previous to taking an impression or to effect delivery of the sheet from the intaglio-engraved-plate after the 30 impression has been taken and while the plate is in motion preparatory to the taking of the next impression. This results in many smudged or otherwise imperfect impressions by reason of this manner of delivery.

35 The insertion of intervening or slip sheets between each succeeding impression is likewise a manual operation which also materially limits the speed at which the printing may be performed.

The main object of my invention is that of 40 providing a mechanical unit for the feeding, printing and delivery of wet or dry paper in sheet, sheets or roll form on an intaglio-engraved-plate, flat bed printing press in such a manner that the paper is placed in the possession of said unit, 45 either mechanically or manually, which unit retains possession thereof during the printing, leaving the intaglio-engraved-plate in exactly the ratio with which the said printing takes place, said paper remaining continuously in possession 50 of said feeding, printing and delivery unit until the said paper is delivered printed side up in its proper position on a conveyor for drying.

A further object of my invention is the delivery 55 of said sheets printed side up upon the carrier which is so timed relatively to the printing of

said sheet that the carrier delivers the paper to an adjoining device, preferably a heating unit, where the wet paper and fresh ink from the impression are dried during its travel through said heating unit. Upon the exit of said paper from the heating unit, the same may be stacked by the usual well-known jogging method of stacking without the use of intervening or slip sheets. 60

A marked advantage resulting from the method of feeding, printing and delivery above referred to, is the uniform registration in the printing of the said sheet or sheets from the said intaglio-engraved-plate or plates. A further advantage resulting from my invention is that sheets of comparatively large dimensions, when handled mechanically in the manner referred to, are handled with dispatch and with far greater speed than has heretofore been possible, avoiding, as it does, the necessary stacking with intervening or slip sheets. 70

My invention will best be understood by reference to the accompanying drawings in which I have illustrated a preferred embodiment and in which—

Fig. 1 is a side view partially broken away of a portion of a printing press embodying my invention; 80

Fig. 16 is a sectional view of the operating means for positioning the gripping elements in receiving position;

Fig. 17 is a fragmentary side view, partially in 15 section, of the positioning device; and

Fig. 18 is a detail view illustrating the frictional device in operative engagement with its associated cam member for actuating the impression 20 roll after the latter has left the printing plate.

Like reference characters indicate like parts throughout the drawings.

Referring now to the drawings, 10 is a bed 25 plate on which is mounted a frame comprising standards 11 and longitudinally extending beams 12 provided with grooves 13 as indicated in Figs. 4 and 6 and in which are received a platen 14 on which is mounted an intaglio-engraved-plate 15. 30 The beams are connected by a cross plate 12a.

The shaft 16a for the impression roll 16 has its bearings in blocks 17 which are preferably yieldingly mounted on compression springs 18 located in recesses 19 in the frame of the machine. 35 The blocks 17 are vertically adjustable by cap screws 20 as best shown in Fig. 6. The impression roll (see Fig. 14) is provided on its periphery with a recess 21 to form what is commonly known in the art as a D-roll. The cutaway portion of 40 the roll in machines of this character is located at the lowermost portion thereof when the platen carrying the printing plate passes beneath the same towards the feeding end of the machine.

It will be understood that the platen carrying 45 the printing plate is reciprocated back and forth from the end of the machine where the ink is applied to the feeding end of the machine. As the actuating mechanism for the platen constitutes 50 no part of my present invention and is well understood in the art, and any well-known form of mechanism therefor may be employed, I have not 55 illustrated the same. It will also be understood that suitable inking, wiping, and polishing mechanisms are also used, but as these elements likewise constitute no part of my present invention, they have not been illustrated.

I will now describe the mechanism by which the 60 impression roll is rotated from the position where the cutaway portion 21 thereof is located at the lowermost portion of the roll through a comparatively small angle to a position where the printing plate engages and rotates the roll.

Referring particularly to Figs. 5, 6 and 7, 65 wherein the impression roll is in the position where the cutaway portion is located at the lowermost portion of the roll as indicated in Fig. 7, the roll is rotated from this position in a clockwise direction to the position indicated in dotted lines, as viewed in Fig. 7, by a cam 22 mounted on a shaft 23. The shaft is in turn actuated by a gear wheel 24 indicated in dotted lines in Fig. 5 which meshes with a gear 25 mounted on a shaft 70 26 and which is driven by a bevel gear 27 meshing

with a bevel pinion 28 on a drive shaft 29 having a bearing at 291.

The cam member 22 engages a roller 30 mounted within an intermediate portion of an arm 31 on a shaft 32, the arm being pivoted as at 33. A link 34 is pivoted at its lower end to the end of the arm 31 while the upper end thereof is pivoted, as at 35, as best shown in Figs. 5, 6 and 7 to a collar 36 secured to a sleeve 37, (see Fig. 6), 80 loosely surrounding the shaft 16a of the impression roll. On the sleeve 37 is also secured the plate or disc 38 on which is pivoted as at 391, a pawl 39 which engages a tooth 40 on a sleeve 41 secured to the shaft 16a of the impression roll. When the cam 22 engages the roller 30, the arm 31 is rotated counter-clockwise, the link 34 is raised and through the described connections rotates the plate 38 and its pawl and thereby rotates the impression roll. The parts are so geared and timed as to cause the foregoing operation to bring the portion of the impression roll adjacent to the cutaway portion 21 directly below the axis of the roll as indicated in Fig. 14.

I preferably provide means for disabling the 100 mechanism by which the impression roll is rotated by the cam 22. This mechanism comprises a lever 42 pivoted at 421 which is preferably operated manually by a bar 44 passing through a guide 45 and provided at its outer end with a hand wheel 105 46. The opposite end of said bar is pivotally connected to one end of the lever 42, the lower end of said lever being provided with a roller 43.

When the lever 42 occupies the position indicated by dotted lines in Fig. 7, the roller 43 is 110 out of the path of the pawl 39 and does not interfere with the operation of the impression roll. If the operator desires to prevent the operation of the impression roll by the cam member 22, the lever 42 is placed in the vertical full line 115 position indicated in Fig. 7, and the roller 43 is then in the path of the outer end of the pawl 39, and moves the pawl to the dotted line position indicated in Fig. 7 where it is out of engagement with the tooth 40, thereby preventing 120 the cam member 22 from actuating the impression roll.

My invention provides a unit which is, in the embodiment illustrated, in the form of an endless carrier which comprises an element which 125 takes possession of the paper while the latter is in the feeding position, and retains possession of said paper during the printing and until the paper has left the printing unit which comprises the intaglio-engraved-plate and the impression roll. 130 This carrier comprises sprocket chains 47 at opposite sides of the machine and as these chains and the associated parts are the same at each side of the machine, the description of one will suffice for both. The sprocket chain engages 135 sprocket 48 secured to the end of the impression roll as best shown in Fig. 6 and also passes over sprockets 49 and 50 located above the impression roll and mounted in the frame as indicated in Fig. 1. The chain also passes over a sprocket 51 140 located adjacent to the feeding device indicated generally at 52. The parts are so designed that the chains 47 move at the same speed as the surface speed of the impression roll.

The feeding device comprises a feed board 53 145 and a gauge 54 against which the edge of a sheet of paper which is to be printed is laid. While I have illustrated a device for the manual placing of sheets of paper in the possession of said feeding, printing and delivery mechanism, it 150

will be understood that the placing of said paper in the possession of said unit may be manually or mechanically intermittently performed.

In accordance with my invention, the carrier 5 comprises an element, constituting a plurality of such elements, which successively take possession of a sheet or sheets of paper while in feeding position and carry the same between the impression roll and the intaglio-engraved-plate to a 10 position where it is delivered printed side up and above the printing unit. In the specific embodiment of my invention illustrated, four such elements are used.

In the embodiment of my invention illustrated, 15 the element which takes possession of the paper and which is indicated generally at A, (see Figs. 10 and 12), comprises a pair of bars 55 and 56, the ends of which are mounted in locating blocks or heads 57 secured to the sprocket chain 47 as 20 indicated in Fig. 11. The bar 55 is provided with a plurality of spaced collars 58 provided with flattened faces as at 59 forming relatively stationary jaws, while the other bar 56 is provided with a plurality of collars 60 on which are 25 mounted relatively movable gripping or holding jaws 61 which engage the jaws 59.

The jaws 61 of the collars 60 are urged towards the jaws 59 by a coil spring 62 surrounding the bar 56, one end of which spring is secured to a 30 collar 63 secured to the bar 56 and the other end of which is secured to a bar or plate 64 mounted on the bars 55 and 56 as best shown in Fig. 11. The bar 56 is rotated in a direction to move the jaws 61 away from the coating surfaces 59 by means of an arm 65 secured to the bar 56 and which is actuated in timed relation to the movements of the parts of the machine to open the jaws to permit the insertion of a sheet of paper while in the feeding position, and again 40 to open the jaws when the gripping bars have arrived at the proper position for delivering the sheet or sheets to a suitable device, preferably a carrier.

Means are also provided for accurately positioning the gripper bars when they take possession of the paper, and also at the time that the impression is being taken. The gripper element is accurately positioned with reference to the edge of the paper and takes possession of the paper 45 prior to the impression and preferably while the paper is in the feeder, at a predetermined distance from and parallel with the edge thereof, and the gripper elements are again accurately positioned at the time that the impression is 50 about to be taken so that the impression is accurately placed upon the paper at a predetermined distance from and parallel to the edge thereof.

I will now describe the means for positioning 55 or registering the gripper bars to take possession of the paper while in the feeding position and for actuating the gripper elements while in this position. The parts located at each side of the machine for accomplishing the foregoing objects 60 are the same and both mechanisms are actuated by a common member, and the parts at one side of the machine only, therefore, will be described.

The positioning head 57 is provided on its outer face with a conical recess 66 as best shown in 65 Fig. 16 in which is received the conical end of a plunger 67 which is urged away from the recess by a coil spring 68 which is located in a recess 69 located in the sprocket wheel 51, one end of the spring being seated in the bottom of the 70 recess and the opposite end engaging a collar 70

on the said plunger 67. When the carrier comprising the sprocket chains 47 rotates the sprocket wheel 51 and the plunger carried thereby to the position indicated in Figs. 15 and 16, a plate 71 is raised to force the plunger 67 to the right as 80 viewed in Fig. 16 to engage the recess 66 and thereby accurately position the gripper element with respect to the sprockets 51. It will be understood that while the gripper bars are mounted on and are moved by the carrier, that because of 85 the fact that the gripper bars must of necessity be somewhat loosely mounted on the sprocket chain, there may be a slight movement between the gripper bars and the carrier. By the provision of the plunger and the actuating mechanism 90 therefor, the gripper bars are caused to take possession of the sheet of paper at an exact predetermined position with respect to the edge thereof and while the paper is in the feeder. The plate 71 is provided with a cam 72 (see Fig. 16) 95 which, when the plate is moved upwardly, rides over the outer end of the plunger and forces it to the right, as viewed in Fig. 16, into its seat in the positioning head. The plate 71 is guided in its upward movement by guide members 73 100 (Fig. 17) which may be formed integral with an intermediate and thinner portion 74.

To the plate 71 is secured a block or head 75, the block preferably being adjustably secured to the plate by slots 76 and cooperating screws 105 77. The block 75 engages the end of the arm 65 thereby rotating the gripper bar 56 against the action of the springs 62 and thereby causing the jaws 61 to move away from the cooperating jaws 59 and thus enabling the operator to feed a 110 sheet of paper between the jaws, at the same time positioning the rear edge of the sheet against the stationary gauge 54 on the feed plate, so that when the jaws close they grip the paper at a predetermined distance from the edge thereof and 115 parallel thereto.

The plates 71 and the head 75 carried thereby are actuated by a cam 78 secured on the shaft 23. The cam 78 engages a roller 79 secured on an arm 80 pivoted on the frame as at 81 (Fig. 3). 120 The free end of the arm 80 is connected by a link 82 to one arm 83 of a bell crank lever pivoted at 84, the other arm of said bell crank lever 85 being connected to a link 86, the opposite end of which is provided with a recess 87 in which is received 125 a pin 88 secured on the end of an arm 89, said arm being secured to a shaft 90 extending transversely of the machine as indicated in Fig. 2. Arms 91 are secured to the shaft 90 at each side of the machine and are pivotally connected by 130 links 92 to the respective plates 71. The plates 71 are urged downwardly by a spring 93 (Fig. 3) surrounding a bar 94 slidable in a bracket 95, one end of the bar 94 being attached to an arm 96 secured on the shaft 90. One end of the spring 135 93 engages the bracket 95 as best shown in Fig. 3 while the other end of said spring engages an adjustable nut 97 on the bar 94.

Means are also provided for exactly positioning the gripper bars with respect to the impression roll when the latter arrives at a position to impart the impression to the paper at an exact predetermined distance from the edge thereof, remembering that the gripper element has grasped the paper at a predetermined distance from the 145 edge. The sprocket wheels 48 are each equipped with a plunger 98 (see Fig. 6) generally similar to the plunger 67 heretofore described but provided with a head 99, a spring 67a being located between said head and the end wall of a recess 150

69a in the sprocket 48. A ring 100 preferably formed of hardened metal is mounted in a recess 101 in the bearing block 17, which the head 99 of the plunger engages during the major portion 10 of the rotation of the impression roll. The ring 100 is provided with a recess 100a in which is located a head 102 beveled at one end as best shown in Fig. 8 and which is urged outwardly by a spring 103 one end of which engages the stem 104 on which the beveled member 102 is mounted, and the opposite end of which engages an adjustable plug 105 which is received in an enlarged end of the opening 106 in which the spring 103 and stem 104 are also received.

15 The impression roll and the associated parts are so timed with respect to the gripper elements A that when the plunger 98 arrives at the position where it is in a line, or substantially in a line, normal to the tangent of the sprocket chain 47 with the sprocket 48, the head 99 of plunger 98 engages the beveled head 102 which is resiliently mounted in recess 100a in ring 100 and forces plunger 98 into engagement with the recess 66 in the locating head of the holding element and thereby exactly positioning the gripper elements 25 with respect to the carrier and the impression roll.

The object of resiliently mounting the beveled member or cam 102 is to prevent the plunger 98 from binding in the event it does not register with the recess 66 in head 57. It is obvious that the head 57, being mounted and carried by the chains 47 will not be in a position to be held by the plunger 98 in the sprocket 48 until the portion 35 of the chain 47 carrying the head 57 engages the sprocket and brings the recess 66 opposite plunger 98. Because of the fact that the chain approaches the sprocket at an angle depending on the relative positions of sprockets 48 and 51, the plunger 98 will not be in a position to engage the recess 69 until they substantially coincide on the line normal to the line of tangency between the chain and the sprocket. Obviously, a rigid cam would tend to push plunger 98 into the recess 66 before this point was reached, thereby causing the two elements to bind which might result in serious damage. From the foregoing it is obvious that the possibility of such a result has been eliminated by my invention.

50 The gripper element A is received in the recess or cutaway portion 21 of the impression roll as best shown in Figs. 4 and 14.

I have described the means by which the impression roll is rotated from the position where the cutaway portion 21 occupies the lowermost portion of the roll, to the position indicated in Fig. 14 where the impression roll is ready to be engaged by the intaglio-engraved-plate 15 on the platen 14. At this time, it will be understood that the platen carrying the plate 15 has been moved to the right of the impression roll, and the gripper element A is now located within the cutaway portion 21 of the impression roll, and has retained its possession of the paper from the time that it took possession of the paper at the feeder in the manner previously described. The platen 14 and the intaglio-engraved-plate 15 carried thereby are now moved to the left as viewed in Fig. 14, and the intaglio-engraved-plate engages the sheet of paper, the friction between the parts being sufficient to cause the intaglio-engraved-plate to rotate the impression roll, which rotation continues until the intaglio-engraved-plate has left the roll.

75 During the time that the intaglio-engraved-

plate is rotating the impression roll, the gripper element A continues its possession of the sheet of paper and retains its possession until the paper is released at the delivery position. After the intaglio-engraved-plate has left the impression roll, means are provided for continuing the rotation of the roll by the driving mechanism until the cutaway portion of the roll arrives at the lowermost position, a few degrees counter-clockwise of the position shown in Fig. 14. The mechanism for positively actuating the impression roll at this time is best shown in Figs. 9 and 18 and comprises a friction roll 107 mounted on a shaft 108 on which is also mounted a sprocket 109 which is engaged by a sprocket chain 110 passing over a sprocket wheel 111 on the drive shaft 26. At the time that the intaglio-engraved-plate leaves the impression roll, a cam member 112 mounted on a head 113 engages the friction roll 107, so that the friction roll continues the rotation of the impression roll, the cam member 112 being of sufficient length to rotate the impression roll to the position where the cutaway portion 21 is located at the lowermost portion of the roll. When the impression roll arrives at the desired position, a segment 114 of a ring which is secured to the head 113 and which is preferably provided with square ends as best shown in Fig. 9, engages a yieldingly mounted plunger 115 which is urged upwardly by a spring 116 mounted in a recess 117 formed in one arm 118 of a lever, the other arm 119 of which is provided with a roller 120 which is actuated by a cam member 121 mounted on a counter shaft 122.

The parts are so timed that the plunger 115 engages one end of the segment 114, as indicated in Fig. 9, at the time that the impression roll is brought to its final position where the cutaway portion occupies the lowermost portion of the roll. A detent 123 forming one arm of a bell crank in the specific embodiment illustrated and pivoted at 128 is caused to engage the opposite end of the segment 114 in order to prevent rebound of the impression roll. The detent is urged to the position indicated in Fig. 9 by a coil spring 124 located in a recess 125 of the frame, the coil spring engaging the lower end of the recess and a plunger 126 engages the other arm 127.

When the impression roll has been positioned in the described manner the continued rotation of the parts causes the cam 121 to leave the roll 120, and a spring 129 surrounding a bar 130 causes the arm 119 to be moved to the left, as viewed in Fig. 9, and the plunger 115 to be moved away from the segment 114 and thereby release the impression roll for the next succeeding movement. One end of the spring 129 engages a stationary part or guide 131 for the bar 130 while the opposite end thereof engages an adjustable nut 132.

A conveyor, indicated generally at B, on which the paper is delivered printed side up is also provided. This conveyor, which moves transversely of the first carrier, may, if desired, comprise a plurality of independent endless flexible belts 133 formed of suitable material such as stout cord which pass over an actuating roll 134 and an adjustable idle roll 135. The roll 134 is actuated through suitable gearing in a casing 136 as best shown in Fig. 1 by means of a pulley 137 engaged by a belt 138 the lower end of which, after passing over suitable idlers 139, engages a pulley 140 on a shaft 141. The milled roll 142 engages a milled member 143 mounted on the shaft 23. The movement of the conveyor is in-

intermittent and is so timed with reference to the movement of the carrier, that it is at a dwell at the time the paper is released by the gripper bars and dropped thereon.

5 As heretofore stated, the gripper element A retains its possession of the paper until it arrives at a position where it releases the paper and permits it to fall upon the conveyor B. When the paper receives its impression, the ink is, of course, 10 on the lower side of the paper and, as it is carried along by the said unit, along the top run of the carrier, the position of the sheet of paper is inverted; that is to say the printed side of the paper now is the upper side of the paper. The 15 paper is released when in position above the carrier B by the engagement of cams 144, mounted on the frame, with the arms 65 which opens the jaws 59 and 61 in a manner similar to that which takes place when receiving the paper from the 20 feeder. Wipers 150, depending from a rod 160 which is mounted transversely of the machine, serve positively to remove the printed papers from between the jaws 61 and 59 of the gripper elements.

25 A second conveyor 145 (Fig. 2) is also preferably provided for taking the paper from the second carrier and delivering it to the oven through which the paper passes and in which it is properly dried.

30 A manually operated wheel 146 is preferably mounted on the shaft 16a of the impression roll to provide for any slight movement.

The operation of my invention will be understood from the foregoing description and is as 35 follows:

Assume that the impression roll occupies the position where the cutaway portion 21 is located at the lowermost portion of the said impression roll as indicated by dotted lines in Fig. 14. When 40 the impression roll is in this position, the platen with the intaglio-engraved-plate moves from the end of the machine where said intaglio-engraved-plate is inked to the feeder end of the machine, the cutaway portion of said impression roll permitting the platen to move underneath it.

At this time one of the gripper elements A occupies the position illustrated in the dotted line position in Fig. 15 with the jaws of the element about to be opened to the dotted line position and ready to receive a sheet of paper, while the next element to the left on the carrier is located in the cutaway portion of the impression roll as indicated by dotted lines in Fig. 14. The locating mechanism comprising the plungers 67 and 45 98 locate the end plungers or heads of the gripper elements in an exact predetermined position relatively to the carrier, with the jaws of the gripper element adjacent to the paper, open, and those in the cutaway portion of the impression roll, closed.

Now, while the platen 14 and the intaglio-engraved-plate mounted thereon move from the right toward the left to a position as indicated in Fig. 14, the mechanism shown particularly in Fig. 5 which moves the impression roll from the position where the cutaway portion 21 is located as indicated in dotted lines in Fig. 14 to the full line position indicated therein, now comes into play, the impression roll when thus moved occupying a position where the periphery of said impression roll immediately adjacent to the cutaway portion 21 is at the point of tangency with the top of the intaglio-engraved-plate 15. The movement of the platen and the intaglio-engraved-plate 15 then moves the impression roll until it has left the in-

taglio-engraved-plate 15. The friction roll 107 then engages the cam 112 and continues the rotation of the impression roll to the first position assumed; that is, where the cutaway portion of the impression roll occupies the dotted line position indicated in Fig. 14.

80 Just before the rotary carrier on which the gripper elements are mounted and the impression roll again begin to move, the plate 71 and the parts mounted thereon are depressed, thereby releasing the arm 65 shown in Fig. 15 and permitting the jaws 61 and 59 to grip and take possession of the sheet of paper. The initial movement of the impression roll from the dotted line position of the cutaway portion indicated in Fig. 14 moves the lower run of the carrier as indicated in Figs. 1 and 3 to the left, carrying the gripper element at the feeding end with it; this gripper element now

85 gripping the paper. As soon as the plunger 98 rides off from the head or cam 102, the gripper element A is unlocked from the associated sprockets. At the same time, the gripper element that is located in the recess 21 in the impression roll, is accurately positioned with respect thereto by the

90 plunger 98 so that the impression is made on the paper in exactly the desired position. The gripper element is then moved in exact synchronism with the impression roll and at the same relative speed as the surface speed thereof. As the gripper element A of Fig. 14 moves upwardly towards the

95 sprocket 49, it still retains its possession of the paper, thereby preventing either tearing or crumpling the paper. This feature is of par-

100 ticular importance where the paper is wet and where the degree of moisture may vary under

105 varying conditions.

110 During the succeeding movements of the said unit, the paper is now carried along with the gripper element over the shaft for the sprockets 49 and then along the upper run of the carrier. At

115 this time the position of the sheet of paper has been inverted; that is to say, the printed side of the sheet which was below where the impression is

120 taken now is the upper side of the sheet and when the gripper element arrives at the cam 144 the

125 jaws of the gripper element are again opened, thereby permitting the paper to fall printed side up upon the conveyor B which moves across the upper portion of the machine. At the same time

130 that the printing operation is carried out, the conveyor moves the paper along to the conveyor

135 143 which delivers the paper to the drying element printed side up and without smudging or offsetting of the ink.

140 While I have described my invention in its preferred embodiments, it is to be understood that the words which I have used are words of description rather than of limitation and that changes within

145 the purview of the appended claims may be made without departing from the true scope and spirit of my invention in its broader aspects.

150 What I claim is:

1. In an intaglio-engraved-plate, flat bed printing press, an intaglio-engraved-plate, an impression roll cooperating therewith, a unit comprising an element for holding a sheet of paper,

140 means for causing said element to take possession of said paper prior to the taking of an impression, said element retaining possession of said paper during the taking of said impression be-

145 tween said impression roll and said intaglio-en-

145 graved-plate, and after said paper has left said intaglio-engraved-plate and said impression roll,

145 said element moving at the same speed as the surface speed of said impression roll, a paper re-

150

ceiving device, and associated means for delivering the paper from said unit to said paper receiving device printed side up.

2. In an intaglio-engraved-plate, flat bed printing press, an intaglio-engraved-plate, an impression roll cooperating therewith, a paper feeder, a unit movable with said impression roll and comprising an element for taking possession of said paper while in said feeder, said element retaining possession of said paper during the taking of an impression and after said paper has left said intaglio-engraved-plate and said impression roll, said element moving at the same speed as the surface speed of said impression roll, a paper receiving device, and associated means for delivering the paper from said unit to said paper receiving device printed side up.

3. In an intaglio-engraved-plate, flat bed printing press, an intaglio-engraved-plate, an impression roll cooperating therewith, a paper feeder, a unit movable with said impression roll and comprising an element for taking possession of a sheet of paper while in said feeder, said element retaining possession of said paper during the taking of an impression and after said paper has left said intaglio-engraved-plate and said impression roll, said element moving at the same speed as the surface speed of said impression roll, a conveyor, and means coacting with said element for delivering said paper therefrom to said carrier printed side up.

4. In an intaglio-engraved-plate, flat bed printing press, a printing unit comprising an intaglio-engraved-plate and an impression roll cooperating therewith, said impression roll being provided with a peripheral recess extending longitudinally thereof, a carrier having a portion located above said impression roll and provided with an element for taking possession of a sheet of paper, cooperating means for causing said element to take possession of said paper prior to an impression, said element being so formed as to be received in said recess and pass between said impression roll and said intaglio-engraved-plate, and retaining possession of said paper while receiving the impression and until said paper has left said unit, the speed of said carrier being the same as the surface speed of said impression roll, and associated means located above said impression roll for causing said element to release and deliver said paper printed side up.

5. In an intaglio-engraved-plate, flat bed printing press, a feeding, printing and delivery unit comprising an intaglio-engraved-plate and an impression roll cooperating therewith, said impression roll being provided with a peripheral recess extending longitudinally of said impression roll, a carrier provided with an element for taking possession of a sheet of paper, cooperating means for causing said element to take possession of said paper prior to an impression, said element retaining its possession of said paper while receiving said impression and until said paper has left said unit, the speed of said carrier being substantially the same as the surface speed of said impression roll, a conveyor for receiving the printed sheet of paper, and associated means located above said impression roll for causing said element to release and deliver said paper on said conveyor printed side up.

6. In an intaglio-engraved-plate, flat bed printing press, a feeding, printing and delivery unit comprising an intaglio-engraved-plate and an impression roll cooperating therewith, said impression roll being provided with a peripheral

recess extending longitudinally thereof, an endless carrier provided with an element for taking possession of a sheet of paper, cooperating means for causing said element to take possession of said paper prior to an impression, said element being so formed as to be received in said recess and pass between said impression roll and said intaglio-engraved-plate while retaining possession of said paper, a conveyor, and means for delivering the paper from said carrier to said conveyor printed side up.

7. In an intaglio-engraved-plate, flat bed printing press, a flat bed intaglio-engraved-plate, an impression roll cooperating therewith, an endless carrier driven by said impression roll at the same speed as the surface speed of said impression roll, said carrier comprising an element for taking possession of a sheet of paper prior to an impression and continuing its possession of said paper during said impression and until it has left said intaglio-engraved-plate, a conveyor, and means for delivering the paper from said carrier to said conveyor printed side up.

8. In an intaglio-engraved-plate, flat bed printing press, a flat bed intaglio-engraved-plate, an impression roll cooperating therewith and provided with a recess, an endless carrier actuated in unison with and at the same speed as the surface speed of said impression roll, said carrier comprising an element for taking possession of a sheet of paper prior to an impression, said element being received in said recess and retaining its possession of said paper during said impression and until it is free of said intaglio-engraved-plate, a conveyor, and means for delivering the paper from said carrier to said conveyor printed side up.

9. In an intaglio-engraved-plate, flat bed printing press, an intaglio-engraved-plate, an impression roll cooperating therewith, an element for taking possession of a sheet of paper, means for causing said element to take possession of said paper at an exact predetermined portion thereof, means for again exactly positioning said element immediately prior to the impression on said paper, said element retaining its possession of said paper during the said impression and until said paper has left the intaglio-engraved-plate, said element moving at substantially the same speed as the surface speed of said impression roll, a conveyor, and means for delivering the paper from said carrier to said conveyor printed side up.

10. In an intaglio-engraved-plate, flat bed printing press, an intaglio-engraved-plate, an impression roll cooperating therewith and provided with a peripheral recess extending longitudinally thereof, a paper feeder, a movable element for taking possession of a sheet of paper, means for causing said element to take possession of said paper while in said feeder, said element being received in said recess of said impression roll and passing between said impression roll and said intaglio-engraved-plate while retaining possession of said paper, means for exactly positioning said element with respect to said feeder and means for again exactly positioning said element with respect to said impression roll and immediately prior to said impression, whereby said element takes possession of said paper and said impression is made at exact predetermined portions thereof, said element moving at substantially the same speed as the surface speed of said impression roll.

11. In an intaglio-engraved-plate, flat bed

printing press, a feeding, printing and delivery unit comprising an intaglio-engraved-plate and an impression roll cooperating therewith, said impression roll being formed on its surface with 5 a recess, an endless carrier comprising an element to take possession of a sheet of paper prior to an impression and retain possession thereof during said impression, a conveyor located above said impression roll, the said carrier inverting said paper during its movement to the upper run of said carrier, and associated means for releasing said paper while being moved by the upper run of said carrier, whereby said paper is delivered to said conveyor printed side up.

printing press, an impression roll having a peripheral recess extending longitudinally thereof, a feeding, printing, registering and delivery unit comprising an element for taking possession of a sheet of paper, means for registering such element while taking possession of said sheet independently of said impression roll, said element being received in said recess during an impression, means for registering said element with respect to said impression roll during an impression, means for continuing possession of said sheet of paper until delivered with its printed side up.
